(57) **CLAIM**

The ornamental design for a joint driving member for robot, as shown and described.

DESCRIPTION

FIG. 1 is a front perspective view of the front, right, and top sides of a joint driving member for robot showing our new design;

FIG. 2 is a rear perspective view of the rear, left, and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a part 9 of FIG. 2; and,

FIG. 10 is a right side view showing a state where a hinge angle is changed.

The broken lines shown represent unclaimed subject matter of the joint driving member for robot or environments and form no part of the claimed design.

The dash-dot lines represent the boundary between the claimed design and unclaimed design and form no part of the claimed design.

The dash-dot-dot lines represent the locations and borders of an enlarged view showing details and form no part of the claimed design.
